COMBINATION AWNING AND SHUTTER

Henry A. Johnston, Winnipeg, Manitoba, Canada

Application May 31, 1932, Serial No. 614,378
In Canada May 6, 1932

7 Claims. (Cl. 189—55)

My invention relates to improvements in combination awnings and shutters particularly those adaptable for use on verandahs, porches, sleeping balconies and the like, and the objects of 5 my invention are to provide combination awnings and shutters that can be easily and quickly closed from the interior of the verandah, porch, or sleeping balcony when desired, and which can be as easily and quickly opened to any desired 10 angle, and at the same time will give a neat and desirable awning effect.

My invention also relates to the operating mechanism of the combination awnings and shutters and to a verandah design with sectional detachable screens.

Referring to the drawings:

Figure 1 shows a full angle view of all working mechanism and parts of the post and frame of awnings and shutters to which such mechanism is attached.

Figure 2 is a plan view of my articulated metal covered lever arrangement used for raising the upper awning.

Figure 3 is a plan view showing one of the sections of the operating lever for the upper awning.

Figure 4 shows an interior face view of a verandah equipped with combination awnings, shutters and operating lever.

Figure 5 shows an exterior front and part end view of a verandah, equipped with said combination awnings and shutters.

Fig. 6 is a fragmentary perspective showing of the cam action friction lock in situ used in 35 association with my invention.

Figs. 7, 8, and 9 consist of an opened out perspective representation of the cam action friction lock in which:

Fig. 7 shows the cover plate and cam track.

Fig. 8 shows the slideable member and bearing plate.

Fig. 9 shows the base plate and attaching ears.

In the drawings, like characters of references 45 indicate corresponding parts in the several figures.

Referring to the drawings:

In Figure 1, 1 represents a part of the centre post between two sections of screen to which all 50 principal mechanism is attached for the operation of the awnings and shutters; 2 represents a fragmentary view of part of the frame of an upper awning to which operating lever 9 is attached; 3 indicates the loop spring, hereinafter 55 explained; 4 represents the wooden plate at-

tached by screws to the post 1, such plate containing locking and operating devices and aperture through which lever 9 and arm 14 operates; 5 represents a cam; 6 represents a metal slot cover; 7 represents a metal plate; 8 represents the slot through which lever 9 functions; 9 represents an operating lever for the upper sections of the combination awning and shutter; 10 indicates one of the several safety notches made in the lever 9; 11 represents the hand grip 10 at the inside lower end of lever 9; 12 represents the metal slide slot cover for slot 13, through which slot operating arm 14 functions; 13 represents slot through which arm 14 operates; 14 represents the arm for operating the lower sections 15 of the combination awning and shutter; 15 represents the chain attached to the inside end of arm 14 for the purpose of lowering or raising the lower section 17 of the combination awning and shutter; 16 represents a ring 20 to be used as a hand grip attached to chain 15; 17 is a fragmentary view of a part of a lower section of the combination awning and shutter; 18 represents a catch notch to engage slot cover 12 for the purpose of locking arm 14 and to hold said lower section of the awning in a fixed position; 23 represents a small bar attaching the cam 5 to slot cover 6.

In Figure 2, 9 represents a view of part of the operating lever 9 for upper section 2 of the combination awning and shutter, showing loop spring 3 and position thereof in the metal casing at the outer end of lever 9 where it is attached to the upper section of the combination awning and shutter. The purpose of said loop spring is to 30 cause a downward tension on lever 9 between points 1 and 2 in Figure 1, which causes lever 9 to remain straight also serving to prevent lever 9 from buckling at the hinge joints and also holding lever 9 against plate 7 until released by the 40 operator.

Figure 3 shows one of the jointed or hinged sections of lever 9. 10 represents one of the several safety notches in lever 9, which engage as desired the top edge of plate 7 located on plate 4, 45 thus preventing further inward movement of lever 9 until released from notch by operator.

In Figure 4, 19 indicates detachable frame screens preferably made of rectangular light wooden frames having screening material covering the same; 20 indicates a screen door; 9 indicates the operating lever 9 when both the upper and lower sections of the combination awning and shutter are closed.

In Figure 5, 21 indicates detachable hinges at- 55

taching both the upper and lower sections of the combination awning and shutter to the top rail or board 22 of the verandah, or to the uppermost board or rail 22 of the lower part of the verandah as the case may be; 2 indicates sectional views of the upper sections of the combination awning and shutter at different angles or degrees closed shut or partly so; 17 indicates sectional views of the lower part of the combination awning and shutter at different positions either up or down; 20 represents a screen door which may be also equipped with upper and lower sections of the combination awning and shutter; 19 represents detachable frame screens already mentioned in connection with Figure 4; 15 indicates a chain attached to arm 14 both used in operating the lower section 17 of the combination awning and shutter up or down as desired and more clearly shown in Figure 1; 9 indicates operating lever for the upper section of the combination awning and shutter. 14 indicates arm and chain for operating lower shutter section 17.

As many sections of the combination awning and shutter may be used on a verandah as required depending on the area to be equipped. The verandah is of the usual open front type, having the front partially closed by boards 22 at the lower part of same to a point where the screen openings 19 begin as shown in Figures 4 and 5 there being the usual sections divided by posts between the screens (see Figure 4). The screen door 20 may also be provided and may be fitted up with sections 2 and 17 as desired.

To the uppermost edge of the uppermost board 22 (See Figure 5) at the base of the opening for screens 19 the lower shutter section 17 is pivotally connected by hinges 21. Said lower shutter sections are in the form of substantially rectangular light durable wood frames having awning material or canvas covering the same. This lower shutter section 17 is so arranged that it can be swung down into the full open position or swung up and completely closed as shown in Figure 5. Said lower shutter sections 17 are provided with operating arms 14 with chain 15 and a hand grip 16 in the form of an attached ring which passes through a suitable slot 13 formed in plate 4 and post 1.

The outer end of operating arm 14 is attached to the frame of the lower shutter section 17. The said lower shutter section 17 is lowered to a full open position or completely closed by swinging it up from the interior of the verandah by manipulating operating arm 14 chain 15 and hand grip 16 through slot 13.

On plate 4 affixed to the interior side of post 1 immediately over slot 13 there is a metal movable slide 12 to engage notch 18 located in operating arm 14 when it is desired to close lock or keep rigid the lower shutter section 17. This metal slide is also employed to totally close slot 13 when lower shutter section 17 is in the down or open positions as shown in Figure 5.

To the top rails or boards 22 of the verandah are hinged the upper awning sections 2 which are formed from substantially light durable wood rectangular frames having canvas awning material covering same.

To the lower inner side of each upper awning section 2, a jointed lever 9 is attached by means of two screws, this lever passing through a suitable slot 8 provided in one of the verandah posts and also through the slot 8 in the plate 4 secured to the inner face of the posts.

75 The locking cam 5 is an ordinary draw-back

window-cam attached to plate 4 at one side of lever 9 with the draw-back face of the cam lying against one side of the said lever. One may lock lever 9 in any desired position by locking the cam at which time the lever 9 becomes jammed between the draw-back face of the cam and the opposite side of slot 8 through which lever 9 operates.

The locking cam 5 consists of a base plate 24 which is attached to the plate 4 by means of ears 10 and within the recess 26 upon the base plate, is provided a slidable member 27 having a bearing plate 28 and a projecting lug 29. A member 27 is situated within the recess 26 and is free to slide forwardly and backwardly therewithin. 15 The cover plate 30 is provided with a lever 31 and a central shank 32, the shank extending through the elongated orifice 33 in the member 24 and being spread or riveted on the rear side of the orifice 34 in the centre of the base plate 24. An 20 eccentric track 35 is provided upon the inner face of the member 30, the projection 29 being received into this track.

As the member 30 is secured onto the base plate 24 by means of the shank 32, it will be obvious that when the lever 31 is actuated, the projection 29 must move in the track either towards or away from the shank 32. In this way, the bearing surface 28 is actuated forwardly or backwardly so that in one direction, the bearing 30 surface will be pressing against the arm extending through the orifice 8 and in the other position, will be reciprocated so that the arm may slide freely.

Plate 7 is attached to plate 4 underneath lever 35 9 flush with the bottom of slot 8.

Lever 9 is provided with safety notches 10. On releasing cam 5 the weight of the upper awning sections 2 tends to push lever 9 in towards the operator if he has not a firm hold on lever 9. 40 Such safety notches automatically engage with the upper edge of plate 7 thus preventing further inward trend until the operator releases such notch.

The upper awning sections 2 are opened partially opened or closed by manipulating lever 9 outward or inward through slot 8 in post 1 and plate 4. The lever 9 can be held at any desired fixed position by means of cam 5 and the safety notches 10 as already explained.

Lever 9 protruding from the inside of the verandah may be folded down in a vertical position parallel and close to the posts 1 through which it passes thus avoiding interference with any one passing or with other things inside the 55 verandah. The lever 9 being jointed allows this to be done.

On stormy days or when it is desired to totally exclude the sun or weather, one will completely close the upper and lower sections such sections 60 being constructed so that both upper and lower sections meet when closed and the ornamental fringe or edge of the upper awning overlies and covers the crack between the sections, thus providing a sun, wind, rain, and weather-proof combination shutter. On the other hand one may open either or both the upper or lower sections at which time the upper section can be adjusted to any desired position, providing a very useful and attractive awning and at the same time the 70 lower section 17 may be left up or swung down as desired. The screen doors may be equipped with the combination awning and shutter if desired. The lower shutter section 17 may be swung up and closed and the upper awning sec- 75

tion 2 partially opened allowing any desired space within limits for the entry of fresh air. In this way, the verandah may be used at night for sleeping purposes, any view from the street being 5 obstructed while at the same time, affording protection from the weather. The lower shutter section 17 may be swung up and completely closed leaving the upper section 2 at any desired position as an awning, thereby raising the lower wall 10 of the verandah 12 to 14 inches, more or less, depending on the size of the lower shutter section, and thus making the verandah more private from the street and at the same time providing a well shaded verandah with plenty of fresh air.

15 I recommend that the sections of the combined awning and shutter be constructed from 4 to 6 or even 8 feet in length, with one set of operating mechanism to each section installed to the post at, or nearest the centre of each section. The 20 upper awning section is recommended to be 30 inches from top to bottom on ordinary verandahs, but may be wider or narrower if desired. The bottom section I recommend to be 12 to 14 inches from top to bottom but this also may be made 25 wider or narrower if desired. Each section of the combined awning and shutter is constructed to meet evenly with the sections on either side on the outside of the verandah posts so that when at the same angle as the adjoining sections form 30 a straight line of awnings or shutters across the verandah.

The combination awnings and shutters are attached to the verandah with loose bolt hinges and may be readily and easily detached, then 35 stored away for the winter if desired, and as readily and easily replaced, thus adding to the life of the awning cloth.

In addition the verandah may be equipped with detachable screens that may be easily removed from the inside of the verandah and if desired glazed sash may be used instead of screens or partly so. The sectional verandah design for 40 said screens is shown in Figure 4. These detachable screens when being installed are designed to slip into grooves provided for that purpose at the top of the window frame, only one button at the bottom being necessary to fasten them securely.

A feature of this combined awning and shutter 50 together with such removable screens or glazed sash is that when glass is used instead of screens some of the combination awning and shutter sections could be closed, the remainder of the sections left open, with the open sections furnished 55 with the glass sash allowing a view to be obtained through the glass windows and at the same time have a fully closed verandah.

When glazed glass sashes are used instead of screens the combination awning and shutter may 60 also be desirable for the purpose of providing an awning, and in addition, a wind, rain, and weather-proof protection. The screens or windows can easily be removed and stored away for 65 the winter and thus add years of life to the screens or windows. Another advantage of the detachable screens is that when the verandah is being closed for the winter one may stretch over and tack on to the outside of the screens cheap 70 canvas and replace the screens in position on the verandah thus providing a weather-proof closed verandah. The canvas can be easily removed from the screens when desired. The verandah is closed in this manner without any 75 heavy labor, and the life of the screens length-

ened. The detachable screens or glazed glass sash are easily fitted up.

The combination awning and shutter, the screens or glass windows, any or all of them, are operated from the inside of the verandah 5 without the necessity of going outside and avoiding heavy work or the use of ladders.

Since various modifications can be made in the above invention, and many apparently widely different embodiments of same, made within the 10 scope of the claims without departing from the spirit and scope thereof, it is intended that all matter contained in the accompanying specification shall be interpreted as illustrative only and not in a limiting sense and I desire only such 15 limitations placed thereon as are specifically expressed in the accompanying claims.

What I claim as my invention, and desire to secure by Letters Patent, is:—

1. The combination with a substantially rectangular, main frame and a stationary upright centrally crossing the main frame, of an awning frame and a shutter frame located at the outer side of the main frame and pivotally connected at their upper and lower edges respectively to the 20 top and bottom of the main frame and adapted in the closed positions thereof to fully close the opening in the main frame, operating means secured to the awning frame and passing slidably through the upright for interior manipulation and 30 operating means secured to the shutter frame and passing slidably through the upright for interior manipulation.

2. The combination with a substantially rectangular, main frame and a stationary upright 35 centrally crossing the main frame, of an awning frame and a shutter frame located at the outer side of the main frame and pivotally connected at their upper and lower edges respectively to the top and bottom of the main frame and adapted 40 in the closed positions thereof to fully close the opening in the main frame, operating means secured to the awning frame and passing slidably through the upright for interior manipulation, operating means secured to the shutter frame and 45 passing slidably through the upright for interior manipulation, means for fastening the shutter frame closed and means for holding the awning frame in selected open positions and for locking the same against opening in its closed position, 50 both of said latter means being operable at the interior side of the main frame.

3. The combination with a substantially rectangular, main frame and a stationary upright 55 centrally crossing the main frame, of an awning frame and a shutter frame located at the outer side of the main frame and pivotally connected at their upper and lower edges respectively to the top and bottom of the main frame and adapted in the closed positions thereof to fully close the 60 opening in the main frame, an operating bar secured to the free edge of the shutter frame and passing slidably through the upright, a flexible pulling member secured to the inner end of the bar, releasable means for locking the bar against 65 movement in the closed position of the shutter, a jointed sectional bar secured to the free edge of the shutter frame and extending slidably through a slot in the upright and means for holding the sectional bar in selected positions within the slot. 70

4. The combination with a substantially rectangular, main frame and a stationary upright centrally crossing the frame, of an awning frame located to the outer side of the main frame and having the upper edge thereof pivotally connected 75

to the top of the main frame, a jointed sectional operating lever having one end attached to the free side of the awning frame and the other end passing slidably through a slot provided in the upright and means for locking the lever against end movement in selected positions of the awning frame.

5. The combination with a substantially rectangular, main frame and a stationary upright centrally crossing the frame, of an awning frame located to the outer side of the main frame and having the upper edge thereof pivotally connected to the top of the main frame, a jointed sectional lever having one end attached to the free side of the awning frame and the other end passing slidably through a slot provided in the upright and the under side thereof provided at suitable intervals with notches and a plate secured to the upright and engageable with the notches in the lever to hold the awning frame in selected open positions.

6. The combination with a substantially rectangular, main frame and a stationary upright centrally crossing the frame, of an awning frame located to the outer side of the main frame and having the upper edge thereof pivotally connected to the top of the main frame, a jointed sectional lever having one end attached to the free side of the awning frame and the other end passing slidably through a slot provided in the upright and

the underside thereof provided at suitable intervals with notches, a plate secured to the upright and engageable with the notches in the lever to hold the awning frame in selected open positions and means carried by the interior face of the upright and releasably engageable with the lever to lock the same against end movement.

7. The combination with a substantially rectangular, main frame and a stationary upright centrally crossing the frame, of an awning frame located to the outer side of the main frame and having the upper edge thereof pivotally connected to the top of the main frame, a sectional jointed lever having one end pivotally connected to the free edge of the awning frame and the other end passing slidably through a receiving slot provided in the upright, a spring associated with the lever and the awning frame at the pivot connection and operating to swing the lever normally downwardly, a plate secured to the inner face of the upright and having a slot therein receiving the lever slidably and the lower end of the slot engageable with suitably spaced notches provided in the under side of the lever, hand actuated means for jamming the lever within the slot in any position of the lever and means for closing the slot opening above the lever in any adjusted position of the lever.

HENRY A. JOHNSTON. 30
